UNITED STATES PATENT OFFICE.

EDWARD A. WAGNER, OF FORT WAYNE, INDIANA, ASSIGNOR TO GENERAL ELECTRIC COMPANY, A CORPORATION OF NEW YORK.

PROTECTIVE DEVICE FOR TRANSFORMERS.

No. 861,003.

Specification of Letters Patent.

Patented July 23, 1907.

Application filed December 18, 1906. Serial No. 348,398.

To all whom it may concern:

Be it known that I, EDWARD A. WAGNER, a citizen of the United States, residing at Fort Wayne, county of Allen, State of Indiana, have invented certain new and 5 useful Improvements in Protective Devices for Transformers, of which the following is a specification.

My invention relates to the protection of transformers and other electrical apparatus employing oil as an insulating medium, and its object is to prevent a burn-out 10 or short-circuit, due to the presence of water which may have found its way into the oil in operation.

It is well known that mineral oils, when freed of moisture, are excellent insulators, and for this reason oil has been commonly used in transformers and other 15 apparatus for insulating purposes. The insulating value, however, falls away rapidly with the introduction of a small quantity of water into the oil, as by sweating of the inside of the casing up to the change in temperature, or in the case of water-cooled transformers, by 20 leakage from the cooling pipes. The presence of .01% of water in mineral oil will lower its value about 50 per cent., and the presence of .1% of water will lower the insulating value about 90 per cent. It is evident from these figures that a small proportion of water may lower 25 the insulating value of the oil sufficiently to cause a burn-out of a transformer coil, but the only way that it has been possible heretofore to ascertain whether water is present in the oil, while the transformer is in service, is to draw off a small amount for testing.

I purpose, by my invention, to indicate the lowering 30 of the insulating qualities of the oil, so that steps can be taken to change the oil before damage has been done to the transformer coil. I accomplish this result by submerging a spark-gap in the oil near the bottom of the 35 casing and impressing a voltage on the terminals of the spark-gap. The spark-gap terminals are far enough apart so that when the oil is free from water, no current can flow from one terminal to the other; but if water is introduced into the oil it settles to the bottom of the cas- 40 ing, reducing the dielectric strength of the oil between the spark-gap terminals, so as to allow a current to jump the spark-gap. This current may be utilized to protect the transformer in any suitable manner.

My invention will best be understood by reference 45 to the accompanying drawing, in which

Figure 1 shows an elevation, with the casing in cross-section, of a transformer provided with a protective device, in accordance with my invention; and Figs. 2, 3 and 4 show different sections of the protective circuit.

In Fig. 1, A represents the transformer casing, which 50 contains the laminated core B and the transformer coils

C, carried thereon. The casing is filled with oil to a level above the transformer windings, thereby insulating them from each other and from the core.

D represent the terminals of a spark-gap which is 55 submerged in oil near the bottom of the casing. These terminals may be connected to any suitable source of voltage. In Fig. 1 they are shown connected in parallel to the primary leads E E. This connection is also shown in Fig. 2, in which C¹ represents the primary and C² the secondary of the transformer. The spark-gap D is connected directly in parallel with the primary. When the dielectric strength of the oil at the bottom of the casing is lowered sufficiently to permit the current to jump the gap, this current may be 60 utilized to blow a fuse F or to trip a circuit breaker in series with the transformer primary.

In place of relying on the current-flow across the spark-gap to actuate an overload protective device in the main circuit of the transformer, the arrangement 70 shown in Fig. 3 may be used. In this figure, a protective device G is inserted in series with the spark-gap and suitably protected by a resistance H. A flow of current across the spark-gap terminals will energize the protective device G, which may be either an indicating device, such as a lamp, to give warning to an attendant, or a magnet coil controlling the transformer 75 circuits.

Instead of impressing the main transformer voltage on the spark-gap, an auxiliary source of voltage, such 80 as the small transformer I, may be employed. This last arrangement is particularly suited for transformers of high voltage, or transformers which are supplied from circuits of high current capacity.

Many other suitable arrangements will be obvious to 85 those skilled in the art.

Further, although I have illustrated my invention as applied to the protection of a transformer, it is obviously equally applicable to other oil-insulated electrical apparatus.

Accordingly, I do not desire to limit myself to the particular construction and arrangements of parts here shown, but aim in the appended claims to cover all modifications which are within the scope of my invention.

What I claim as new and desire to secure by Letters Patent of the United States, is,—

1. In oil-insulated electrical apparatus, in combination with the inclosing casing, a spark-gap submerged in the oil near the bottom of the casing and connected to a source 100 of voltage.

2. In oil-insulated electrical apparatus, in combination with the inclosing casing, a protective circuit comprising

a source of voltage and a spark-gap connected thereto and submerged in the oil near the bottom of the casing.

3. In oil-insulated electrical apparatus, in combination with an inclosing casing, a spark-gap submerged in the oil 5 near the bottom of the casing and connected to a source of voltage, and a protective device in series with said spark-gap.

4. In oil-insulated electrical apparatus, in combination with an inclosing casing, a protective circuit having ex-

posed terminals submerged in the oil adjacent each other 10 near the bottom of the casing.

In witness whereof, I have hereunto set my hand this 7th day of December, 1906.

EDWARD A. WAGNER.

Witnesses:

JAMES J. WOOD,
W. H. CRIGHTON.
